JOHN P. FLIPPEN, OF PITTSBURGH, PENNSYLVANIA

GAS SCRUBBER

Application filed January 6, 1926. Serial No. 79,544.

This invention relates to scrubbers or washers such as are ordinarily employed for removing foreign material from gaseous fluids.

5 An object of the invention is to produce a simple and inexpensive scrubber which is more effective in operation than scrubbers now in use and known to me.

A further object is to produce a gas scrubber in which means are employed for maintaining the efficiency and the effectiveness of the scrubber under varying conditions of operation.

These and other objects are attained by 15 means of apparatus embodying the features herein described and illustrated in the drawings accompanying and forming a part hereof.

In the drawings—
20 Figure 1 is a vertical sectional view of a scrubber embodying my invention;

Fig. 2 is a sectional view on an enlarged scale of a portion of the apparatus shown in elevation in Fig. 1;

25 Fig. 3 is a plan view of a detail of the scrubber embodying my invention; and

Fig. 4 is a plan view of a segment of a grid forming a detail of the invention.

Apparatus of the character herein described is ordinarily employed for the purpose of removing dust or other extraneous materials from gaseous fluids, and in this operation it is necessary to subject all the gas traversing the scrubber to the wetting and cooling action of a washing liquid. It is also essential, from the standpoint of efficiency, to utilize a minimum amount of washing liquid, but under conditions that will give the desired results. For this reason, it is not only de-

40 sirable but almost essential to provide means which will enable the operator or attendant to vary the supply of washing liquid as the supply of gaseous fluid to be washed varies but, at the same time, to employ the washing liquid effectively and to minimize the amount of power utilized during the washing operation.

45 Scrubbers now in use employ means for varying the amount of washing liquid employed but no means are employed in such

scrubbers for compensating for varying flows of liquid in such a way as to maintain a minimum resistance to flow of the gaseous fluid through the scrubbing apparatus and at the same time accomplish effective 55 scrubbing under all variations in flow of gaseous fluid. This advantageous result is attained by means of apparatus embodying my invention. As illustrated, the scrubbing apparatus set forth as a practical embodiment 60 of my invention consists of a chamber 4 provided with a gas inlet port 5, gas outlet port 6, liquid distributing devices 7 and revolving and stationary grids 8 and 9 which are located in pairs and in such relation to the 65 liquid distributing devices that they not only supplement the scrubbing action of the liquid but insure a substantially uniform distribution of the gaseous stream traversing the scrubber so that all portions of the stream 70 are uniformly scrubbed.

The chamber 4 is enclosed by a shell or casing 10 in which the inlet and outlet ports 5 and 6 are formed. The interior of the casing is preferably divided into two compartments by means of a specially formed baffle 11 which also performs the function of collecting liquid which has been employed in the scrubbing operation in the upper of the two compartments. As illustrated, the baffle 75 11 is rigidly secured at its outer circumferential edge to the shell 10, which is preferably cylindrical. This baffle is substantially frustro-conical in shape and is provided at its upper edge with an upwardly extending flange 12 which surrounds a central port 13 formed in the baffle and also co-operates with the baffle in forming a receptacle for scrubbing liquid. The port 13 forms a free passage for the gas from the lower to the upper 80 compartment of the chamber 4 and is shielded by a stationary directing baffle 14 which as illustrated may be mounted on the adjacent stationary grid 9.

85 As has been said, the grids 8 and 9 are located in pairs and, as illustrated, each of these grids is frustro-conical in shape and are so located that their outer edges are located above their centers or inner edges. As shown, each stationary grid is secured to the shell 10 90

by any suitable means, such for example, as an annular flange, shown in the drawings as a spider 15 rigidly secured to the shell, and having radially extending arms 15^a. The 5 inner edge of each grid 9 extends into close proximity with a central shaft 16 which extends centrally through the chamber 4 and on which the rotating grids 8 are mounted.

As shown, the rotating grids are of substantially the same shape and size as the stationary grids and are secured at their centers or inner edges to the shaft 16 by means of spiders 17 rigidly mounted on the shaft. Each grid extends radially from the shaft to 15 a point immediately adjacent to the shell 10 and the relation of each rotating and stationary grid forming a co-operating pair is such that all gaseous fluid traversing the chamber 4 must pass through at least one of 20 the grids of the pair.

As shown in the drawings, three pairs of cooperating grids are located in the upper compartment and two pairs are located in the lower compartment of the chamber 4. It 25 will, however, be understood that any number of such pairs may be located in each compartment.

Each compartment is also provided with a liquid distributing device 7 which as illustrated is a ring surrounding the shaft 16 and provided with a plurality of delivery apertures so located as to discharge a spray or divided stream of liquid which substantially fills the compartment. As shown, each ring 35 7 is substantially half the diameter of the shell 10 and communicates with a source of liquid supply through piping 18 which is provided with suitable control valves 19. A moisture separator 20, shown in the form 40 of a wire gauze, is located in the upper compartment above the ring 7 of that compartment and between it and the outlet port 6.

During the operation of this device, the shaft 16 is driven by a motor 21 at a speed 45 depending upon the diameter of the rotating grids. While varying conditions may make it desirable to vary the speed of rotation of the shaft 16, I now prefer to rotate the shaft at about 20 R. P. M. where the rotating grids are approximately eighteen feet 50 in diameter.

The gas entering the inlet port 5 is distributed by a deflector 22 located above and immediately adjacent to that port and is 55 further distributed as it passes through the grids 8 and 9 of the lowermost pair. It will be apparent that these grids are wet by liquid issuing from the lower ring 7 and passing 60 through the next adjacent pair of rotating and stationary grids. Consequently, the gas, in passing through each pair of co-operating grids is not only broken up into small streams but is subjected to the extended 65 wetted surface of the grids with the result

that the gas is thoroughly scrubbed and cooled.

I will be apparent to those skilled in this art that the scrubbing and cooling operation of the grids is supplemented to some extent by liquid falling through the chamber 4 and that the foreign material carried by the gas is eventually collected by the liquid, even though its removal from the gas is first accomplished by contact with the wetted surface of one of the grids. 70

The gas, after having passed through the co-operating stationary and rotating grids of the lower compartment and through the spray or mass of separate streams of liquid 80 issuing from the lowermost ring 7, is caused to contract toward the center of the chamber in its passage through the port 13. The shield 14, then acting as a deflector, aids in spreading the contracted stream of gas so that it substantially fills the lower portion of the uppermost compartment. This stream then passes alternately through stationary and rotating grids which are wet by a separate supply of liquid issuing from the uppermost ring 7 and finally passes through the separating gauze 20 and the outlet port 6, after having passed through the spray or mass 90 of separate streams of liquid issuing from the uppermost ring 7. 95

One advantage of employing two compartments is that it may be desirable, with certain gases, to employ different washing liquids or liquids of different concentration, and under such circumstances, the two compartments readily contribute to such a use of the apparatus. Another advantage is that, where the same character or quality of washing liquid is employed in each compartment, the heavier and more easily condensable vapors are collected in the lowermost compartment and may be disposed of independently of the liquid and foreign material collected in the uppermost compartment. Another advantage is that the amount of liquid employed may be conserved and used to the best advantage by varying the amount delivered to one or the other of the rings, dependent upon the character of foreign material contained in the gas being scrubbed. 100 105 110 115

In most gas scrubbers employing rotary parts, there is a tendency for the scrubbing liquid to be thrown outwardly toward the shell of the scrubbing chamber with the result that gas traversing the central portion 120 of the chamber is subjected to a minimum scrubbing action. This lack of uniformity in the scrubbing operation is objectionable and is overcome, in the scrubber embodying my invention, by the form of the rotating and 125 stationary grids 8 and 9 employed.

As has been pointed out, these grids are frusto-conical in shape with their outer edges above their centers. With this arrangement, both the rotating and stationary 130

grids minimize the centrifugal displacement of the scrubbing liquid, since the tendency for liquid deposited on a rotating grid to move outwardly across that grid is overcome, or at least materially minimized, by the fact that such outward movement would of necessity also be an upward movement of the liquid. Again, the shape of the stationary grids 9 is such as to offset any slight centrifugal displacement of the liquid, which may be occasioned by the rotating grids, since liquid deposited or thrown onto the stationary grids will tend to move inwardly toward the center of the grids or in a direction opposite to the movement occasioned by centrifugal force. As a result of this arrangement of grids, the entire interior of the chamber 4 will be subjected to a substantially uniform flow of liquid, and there will be little or no tendency for the outer portions of the grids to receive more liquid than is delivered to the inner portions. From this, it will be apparent that the gas will be uniformly scrubbed even though there is a tendency for longitudinal stratification in the gas stream traversing the chamber 4.

Such a tendency will, however, be offset and, as a matter of fact prevented by the grids 8 and 9, since they are preferably so formed as to contribute to a uniform distribution across the chamber of the gas traversing the chamber. This is accomplished by forming the grids of heavy wire gauze and by so constructing the gauze that the resistance to gaseous flow through it will be as low as is consistent with the provisions of the necessary scrubbing action of the gaseous fluid.

As shown in Fig. 3, the grids are made up of radiating wires 23 which are so arranged that the gas passages between them and the interwoven circumferential wires 23^a are not uniform radially of the disk. As shown, the smaller passages are located at an intermediate point of the disk which tends to offset the centrifugal action on the gas itself and also tends to make the resistance through each pair of grids substantially uniform from the center to the periphery of the grid. Another advantage of this form of grid is that it not only presents a maximum wetted surface to the gas passing through it but also resists centrifugal action to which I have referred. It will be apparent that the circumferential wires in effect form barriers which will tend to check outward travel of the liquid on the rotating grids, since if any liquid is thrown outwardly by centrifugal force, some portion of such liquid will be thrown onto an adjacent circumferential wire or barrier 24 and will be broken up and redistributed by that barrier, thereby not only checking the outward movement of the liquid but rendering the liquid less susceptible to centrifugal force by reason of its reduction in mass. In addition, the frustro-conical shape

and the spacing of the grids cause the stationary grid to intercept any liquid thrown outwardly by centrifugal force before it has moved very far toward the shell. Then, too, the barriers will form points of discharge, for centrifugally displaced liquid, with the result that each rotating disk will, under the influence of centrifugal force, discharge a multiplicity of sprays of liquid instead of a single spray at its outer edge. This fact, and also the fact that each grid is inclined upwardly, contributes to the effectiveness of the scrubber, since it will be apparent that the space intervening between each pair of rotating and stationary grids will be more or less uniformly flooded by such annular sprays issuing from the rotating grid, and that therefore, gas moving upwardly through the co-operating pairs will be subjected to a cross stream of liquid as well as to the wetted surface of the stationary and rotating grids.

On the other hand, the circumferential wires 23^a of the stationary grids will not be so effective as barriers to the inward flow of the liquid along the stationary grid, since the flow there will be much slower and the liquid will find its way along the grid without being materially impeded by the circumferential barriers. It will also be apparent that the interweaving of the radial and circumferential wires will form a multiplicity of points on which liquid will collect, and that, therefore, the liquid dropping from the stationary grids will be uniformly distributed across the chamber.

As shown in Fig. 1, the port 13 is shielded by the shield 14. This prevents any substantial amount of liquid from the upper compartment entering the lower compartment and substantially all the liquid employed in the upper compartment may therefore be drawn off through the liquid outlet passage 24 of the upper compartment. In the lower compartment, the liquid outlet port 25 is preferably provided with an upwardly extending flange 26 so that liquid will collect on the bottom of the lower compartment to a predetermined height.

One of the features of my invention is that the distance between the rotating and stationary grids of each pair may be varied to suit the varying conditions of operation.

This is accomplished by so mounting the shaft 16 that it is capable of longitudinal or vertical adjustment, so that each rotating grid may be moved toward or away from its co-operating stationary grid. The advantage of such an arrangement is that washing liquid may be conserved during periods of low flow of gas to be washed, and at the same time the scrubbing may be effectively accomplished. It will be apparent that, as the rotating and stationary grids of each pair are moved together, they increase the resistance to flow of the gaseous fluid, since they in effect co-

operate to reduce the effective area of the gas delivery ports formed in each of them. It will, therefore, be apparent that an increased scrubbing action is obtained by moving the rotating and stationary grids closer together, and that, consequently, less washing liquid need be employed to accomplish the same result. From this, it follows that, as the flow of gas is reduced and as the resistance to flow is consequently reduced, the scrubbing action may be maintained at a maximum, even though the amount of scrubbing liquid employed is reduced, by moving the rotating grids closer to their co-operating stationary grids.

In the drawings, I have illustrated a practical method of mounting the shaft 16 so that its longitudinal adjustment may be accomplished even while the shaft is rotating. As shown, the driving shaft 28, which is shown coupled to the motor 21 in Fig. 1, is provided with a worm (not shown) which meshes with a worm wheel 29 shown in Fig. 2. The hub portion 30 of this wheel is mounted on a thrust bearing 31 and is operatively connected to the shaft 16 by means of a collar 32. The collar 32 is splined to the shaft 16 and the shaft is adjustable to different positions relative thereto by means of a cap nut 33 which is screwed onto the threaded upper end of the shaft, and bears against the collar 32.

The thrust bearing 31 is preferably a roller bearing and the hub portion 30 is also preferably provided with a roller bearing 34 which is located between it and an annular flange formed on the standard or support 35 and surrounding the shaft. The standard 35 is mounted on the shell 10.

With this arrangement, the shaft may be adjusted to different vertical positions even while it is rotating. As shown in Fig. 1, the lower end of the shaft extends into a guide bearing 36 which is protected from moisture within the chamber 10 by means of a collar 37 mounted on the bottom of the chamber 4 and extending upwardly around the shaft 16 in telescoped relation with a downwardly extending sleeve 38 which is mounted on the supporting collar 17 of the lowermost rotating grid.

Another feature of the invention is that the circular grids 8 and 9 are preferably made up of a number of segments as shown in Fig. 4, for the purpose of simplifying the operation, assembling the scrubber and of renewing the grids. For this purpose, the shell 10 is provided with manholes 39, which are of such shape and size that the sectors of the grids may be readily passed through them. The edges of each sector are rigidly secured to the supporting spider in any suitable manner, such for example as by means of bolts not shown.

While I have described the preferred em-

bodiment of my invention, it will be apparent to those skilled in the art that various changes, additions, omissions and modifications may be made therein without departing from the spirit and scope of the invention as set forth by the appended claims.

I claim:

1. In combination in a gas scrubber, a gas washing chamber having a gas inlet port and a gas outlet port formed therein, means for dividing the chamber into two communicating compartments, co-operating stationary and rotary grids mounted in each compartment in the path of gas travel therethrough, means for introducing a spray of separate liquids in each compartment in the path of gas travel passing therethrough, and means in each compartment for collecting and discharging liquid from said spray.

2. A gas scrubber comprising a shell provided with a gas inlet port, a gas outlet port, a liquid inlet, a liquid outlet, and an opening for giving access to the interior thereof, a closure for said opening, a rotatable shaft extending axially through said shell, alternately arranged rotating and stationary grids located within said shell and intervening between said gas inlet and outlet ports, said rotary grids being mounted on and rotated by said shaft and each of said grids being frustro-conical in shape and made up of segmental sections of interwoven wire of such size as to be removable through said opening.

3. In a gas scrubber comprising a shell having a gas inlet port located near the bottom thereof and a gas delivery port located near the top thereof, a rotatable shaft extending axially through said shell, frustro-conical grids of interwoven metal mounted on said shaft, each grid extending therefrom substantially to said shell and intervening between said ports with the outer edge of each grid located above its center, a stationary frustro-conical grid located in cooperative relation with each rotating grid and extending downwardly from said shell substantially to said shaft and means for delivering a liquid spray downwardly through said shell.

4. In a gas scrubber comprising a shell having a gas inlet port located near the bottom thereof and a gas delivery port located near the top thereof, a rotatable shaft extending axially through said shell, frustro-conical grids of interwoven metal mounted on said shaft, each grid extending therefrom substantially to said shell and intervening between said ports with its outer edge located above its center, a stationary frustro-conical grid located in cooperative relation with each rotating grid and extending downwardly from said shell substantially to said shaft, means for delivering a liquid spray downwardly through said shell and means for varying the distance between the rotary and stationary grids.

5. In a gas scrubber comprising a shell having a gas inlet port located near the bottom thereof and a gas delivery port located near the top thereof, a rotatable shaft extending axially through said shell, outwardly extending upwardly inclined woven wire grids secured to said shaft for rotary movement therewith and extending outwardly substantially to said shell, a stationary woven wire grid mounted on said shell adjacent each of said rotary grids and extending inwardly substantially parallel therewith, means for delivering a liquid spray above said grids and means for rotating said shaft.

15 In testimony whereof, I have hereunto subscribed my name this 4th day of January, 1926.

JOHN P. FLIPPEN.
